UNITED STATES PATENT OFFICE

108,663

DESIGN FOR A TEXTILE FABRIC

Paul Reiman, New York, N. Y.

Application December 30, 1937, Serial No. 73,968

Term of patent 3½ years

To all whom it may concern:

Be it known that I, Paul Reiman, a citizen of the United States of America, residing in New York city, in the Borough of Manhattan, county and State of New York, have invented a new, original, and ornamental design for a Textile Fabric, of which the following is a specification, reference being had to the accompanying drawing, forming part thereof, wherein,

The figure is a plan view of a piece of textile fabric showing a complete unit of my design between the two selvage edges of the fabric.

I claim:

The ornamental design for a textile fabric, substantially as shown and described.

PAUL REIMAN.
